193,590

CAMERA FRONT OR SIMILAR ARTICLE

Henry Dreyfuss, South Pasadena, and James M. Conner,
Glendale, Calif., assignors to Polaroid Corporation,
Cambridge, Mass., a corporation of Delaware

Filed June 13, 1961, Ser. No. 65,580

Term of patent 7 years

(Cl. D61—1)

FIG. 2 is a front perspective view; and
FIG. 3 is a rear perspective view thereof.
The dominant features of our design are shown in solid lines in the drawing.

We claim:

The ornamental design for a camera front or similar article, substantially as shown and described.
